UNITED STATES PATENT OFFICE.

LEO F. ADT, OF TROY, NEW YORK.

DESIGN FOR A COLLAR.

SPECIFICATION forming part of Design No. 32,843, dated June 12, 1900.

Application filed April 12, 1900. Serial No. 12,636. Term of patent 7 years.

To all whom it may concern:

Be it known that I, LEO F. ADT, a citizen of the United States, residing at Troy, in the county of Rensselaer and State of New York, 5 have invented and produced a new and original Design for Collars; and I do hereby declare the following to be a full, clear, and exact description of the same, reference being had to the accompanying drawings, forming 10 a part thereof.

Figure 1 is a perspective view of a collar, showing my new design as arranged when in use. Fig. 2 is a perspective view of the same, showing the ends of the collar separated.

15 As shown in the drawings, the leading or material feature of my design consists of the extended end A' of the neckband A and the

ends b of the band B, extending upward in diverging lines from the projecting button-hole-tabs B', so that when the ends of the 20 collar are brought together a portion of the band A' is exposed between the inclined edges b of the band B, as shown in Fig. 1.

What I claim as new, and desire to secure by Letters Patent, is—

The design for a collar as herein shown and described.

In testimony whereof I affix my signature in presence of two witnesses.

LEO. F. ADT.

Witnesses:

ROBERT W. HARDIE,
GEORGE B. YOUNG.
